Primary Examiner — Bridget L Eland(74) *Attorney, Agent, or Firm* — Genius Patent APC;
Bruce Angus Hare(57) **CLAIM**

The ornamental design for a marine radio, as shown and described.

DESCRIPTION

FIG. 1 is a front, top, left-side perspective view of a marine radio showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in the drawings show portions of the marine radio that form no part of the claimed design.
